UNITED STATES PATENT OFFICE.

DONALD G. MACDONALD, OF DETROIT, MICHIGAN.

CONCRETE SIDEWALK.

No. 856,409.

Specification of Letters Patent.

Patented June 11, 1907.

Application filed November 19, 1906. Serial No. 344,013.

To all whom it may concern:

Be it known that I, DONALD G. MACDONALD, a citizen of the United States, residing at Detroit, county of Wayne, State of Michigan, have invented a certain new and useful Improvement in Concrete Sidewalks; and I declare the following to be a full, clear, and exact description of the same, such as will enable others skilled in the art to which it pertains to make and use the same, reference being had to the accompanying drawings, which form a part of this specification.

This invention relates to concrete sidewalk construction, and has for its object improved forms of concrete members which entirely avoid the use of wood, and which are not only cheaper in the first instance, but improve structurally with age.

In the drawings:—Figure 1, is a perspective of a section of walk with the stringers extending past the same at each end. Fig. 2, is an elevation of the end of the walk, showing the relative position of planks and stringers. Fig. 3, is a section of the same. Fig. 4, is a sectional elevation at right angles to the plane of Figs. 2 and 3, and looking lengthwise of a sidewalk as completed.

1 and 2 represent longitudinally extending stringers of concrete, grooved in their upper face, as at 3, throughout their length, and with their ends 1^a, and 2^a, notched in complementary fashion to form a strong joint at their point of union.

4 are the individual planks of a walk along whose under surfaces extend integral projecting strips 5 near each end, which fit into the recessed portions 3 in the stringers. At each end the tread planks 4 extend beyond the stringers, the same as in the ordinary plank walk. The boards and stringers may each, or either, be reinforced as at 9, with any approved form of metal insertion, or they may be left without reinforcement, depending upon the strain which they are expected to carry.

6 are foundation blocks laid in the ground beneath the points of union of the stringer pieces. Like them, they are preferably of concrete, and they serve to prevent the stringers from sagging at these points. Each board has a lateral rib 4^a on one edge, and a corresponding recessed portion 4^b on the other, so that the boards may be fitted the

same as wooden boards. This I regard as a desirable though not an indispensable feature. 55 The cohesion of the boards, due to this, in addition to that caused by the projection of the strip 4 into the recess 3 in the stringers, makes the further use of any securing means, such as nails, entirely unnecessary, especially 60 if, just prior to the insertion of the strips 5, the recessed part 3 is smeared with a coating of nearly liquid cement.

What I claim is:—

1. In a concrete sidewalk, the combination of a tread member having integral projecting holding strips near each end of its under surface, a plurality of rows of stringers having their upper surfaces grooved for the reception of said holding strips, and having the end portions of each stringer formed to interlock with the complementary ends of adjoining stringers, and supporting blocks whereon the meeting ends of the stringers rest, substantially as described. 75

2. A concrete sidewalk, having in combination with unitary stringer members of said material provided with a groove in their upper surfaces and adapted to interlock at their ends with those adjoining, blocks whereon said stringers rest at their ends, and concrete tread members provided with longitudinally extending reinforcing strips and having projecting from their under surface shoulders adapted to engage within the 85 grooves in said stringers, substantially as described.

3. In a concrete sidewalk, the combination of molded stringer members having ends adapted to interlock with those adjacent, their upper surfaces being indented for the reception of complementary projections, blocks beneath the meeting ends of said stringer members, and concrete tread members having projecting portions on their 95 under surfaces adapted to engage in said indentations, each having a complementary rib on one lateral edge and a recessed portion in the other lateral edge, substantially as described. 100

In testimony whereof, I sign this specification in the presence of two witnesses.

DONALD G. MACDONALD.
